UNITED STATES PATENT OFFICE.

JOHN J. THACHER, OF WETHERSFIELD, CONNECTICUT, ASSIGNOR TO PRATT & WHITNEY COMPANY, OF NEW YORK, N. Y., A CORPORATION OF NEW JERSEY.

PROFILING MACHINE.

Application filed January 9, 1920. Serial No. 350,424.

To all whom it may concern:

Be it known that I, JOHN J. THACHER, a citizen of the United States of America, residing at Wethersfield, in the county of 5 Hartford and State of Connecticut, have invented new and useful Improvements in Profiling Machines, of which the following is a specification.

This invention relates to metal working 10 machines and more specifically to profiling machines wherein a rotary cutter is caused in operation to follow a path conforming to a pattern mounted on the machine and it is the particular object of the invention to 15 generally improve machines of this type.

It is a further object of the invention to 20 generally improve the tool lubricating system of metal cutting machines and to provide improved means for more readily disposing of the chips as they are formed during the operation of the machine.

It is a further object of the invention to 25 mount the driving means and cutter-supporting means in an improved manner and to provide an improved and novel means and arrangement for supporting and adjusting the cutter supporting saddle on its guide rails.

It is a further object of the invention to 30 improve the accuracy and utility of profiling machines by mounting the former pin blocks in an improved manner whereby the same may be more easily and accurately adjusted and firmly secured in adjusted positions.

With the above and other objects in view, which will appear as the description proceeds, the invention will now be described by reference to the drawings wherein:

40 Figure 1 is an isometric view of a profiling machine embodying the present invention.

Fig. 2 is an end elevation thereof partially broken away to illustrate certain improved lubricating features, the cutter-supporting saddle being shown in section on the line 2—2 of Fig. 3.

50 Fig. 3 is a front elevation of the saddle and cutter-supporting heads, the improved former pin blocks being shown as mounted in the heads.

Fig. 4 is a plan view of the body of the

machine showing the large chip and oil basin and the integral parts thereof.

Fig. 5 is a vertical longitudinal section 55 thereof on the line 5—5 of Fig. 4.

Fig. 6 is a vertical transverse section taken on the line 6—6 of Fig. 4.

Fig. 7 is a detail plan view of one of the cutter heads having the improved former 60 pin blocks mounted therein, the mounting of one of these blocks being shown in horizontal section taken on line 7—7 of Fig. 8.

Fig. 8 is a detail front elevation of the same, showing one of the block mountings 65 in vertical section taken on line 8—8 of Fig. 7.

Referring more specifically to the drawing by reference characters, 1 indicates the base of the machine and 2 the supporting 70 column on which is mounted the arch or saddle supporting member 3 comprising the rails 4 and 5. As shown in Fig. 1, I prefer

to make the member 3 as a piece separate 75 from the base 1 and to secure the said member to the base abutments 3' by means of bolts 3''. It should be noted that these abutments are entirely within a large chip and oil basin to be hereinafter described.

The saddle 6 is mounted to slide along the 80 rails and vertically slidably mounted therein are the cutter heads 7 which support the cutter spindles 8 and the usual former pins. As is usual in this type of machine, the saddle may be moved along the rails by 85 means of a rack and pinion mechanism 9 and an operating handle 10. The work is adapted to be supported on the table 11 which may be moved on the ways 12 in a direction at right angles to the movement 90 of the saddle by means of a handle 12'. I provide the table with the usual trough 11' and furthermore prefer to provide an overhanging lip 11'' leading from the trough 95 whereby the table guideways are kept free from chips and cutting lubricant.

As heretofore stated, one object of my invention is to provide improved means to care for the oil or lubricating compound and chips coming from the work table and in this connection it should be understood that throughout the specification the term "oil" is used in a broad sense to indicate a lubricant or lubricating or cutting compound. 100

This improved construction is shown in Figs. 1, 2, 4, 5 and 6 wherein I have illustrated a large chip and oil basin 13 preferably integral with the column 2 and entirely surrounding the work table and its supporting guides. As before stated, the rail member 3 is entirely supported within this basin on abutments 3'. Also the rails and cutter operating parts mounted on the rails are directly over the basin whereby any oil dripping from such parts or down the rail supports falls directly into the basin. The base of the machine preferably projects forward as at 14 wherein is provided an oil reservoir 15 with one or more ports leading thereto. I preferably provide two such ports and mount a removable chip screen 16 within each and directly above each of the screens, as shown in Figs. 1 and 2, I support a removable chip pan 17, such construction permitting quick and easy removal of the chips and easy access to the reservoir for cleaning or other purposes. It should be noted that the screen 16 prevents any chips from dropping into the reservoir 15 where the pan 17 is removed. The chip and oil basin 13 preferably extends to the front and rear as shown in Fig. 2 in such manner as to project entirely over the base of the machine and beneath the work table and the inner surface of such basin at all points slants toward the channels 18 leading respectively into the removable chip pans. It should be clear that the novel features herein disclosed may be embodied in machines of designs other than the one shown herein, one of the foremost features of the invention being the large chip and oil basin supported beneath and extending outside of the operating table and a removable oil-draining chip pan so located relative to the basin that it may readily be removed to dump the chips therefrom. During the operation of the machine, the chips as well as the lubricant are caught by the basin 13 as they fall from the table 11, the arrangement preferably being such that the basin performs this function in all positions of the table. It will also be noted that the basin extends beneath all the operating parts of the machine in such manner that any oil dripping from such parts falls into the basin where it is carried to the reservoir 15. I also prefer to provide baffle-plates 19 and 19' at each side of the machine whereby any oil dripping from the outer portion of the rail is deflected into the basin. It will be clear that the shape of the basin 13 is such that the chips and lubricant are washed from the higher levels 13' to the lower levers 13" and down the channels 18 into the removable pans 17 where the lubricant is drained off leaving the chips in the pans. The chips may be easily removed by lifting the pans through the space or opening beneath the channels 18 at the front of

the machine and dumping the chips therefrom. The lubricant is used over again by being pumped from the reservoir by a pump 20 and connections shown in Figs. 1 and 2.

In profiling machines of the present type, it is essential that all operating parts be as rigid and free from looseness and lost motion as possible. With such end in view, I provide a novel means and arrangement for supporting and adjusting the saddle on the supporting rails in an improved manner. This means comprises a taper gib 21 which preferably is of a length to span the entire length of the saddle 6. As shown in Figs. 1 and 2, I form a preferably integral elongated projection 22 on the saddle, such projection being adapted to cooperate with the upper rail-engaging portion 23 in supporting the saddle. I mount the gib 21 between this projection and the upper surface of the lower rail and I provide means, preferably a screw 24 as shown, for adjusting the gib longitudinally to take up any wear or looseness of the saddle on the rail. It will of course be understood that the lower surface of the projection 22 is tapered or inclined to conform to the taper of the gib. By supporting the major portion of the saddle on one rail and by performing all the adjusting operations on a single rail by means of a single elongated gib, the mounting of the saddle is rendered stronger and more accurate than on like machines heretofore used.

As a further means for preventing vibration and rendering the machine more accurate, I prefer to mount the driving drum directly on the body of the machine rather than on the rail member 3 as has been the usual practice heretofore. As shown in Fig. 1, I secure the brackets 25 directly to the machine body at 25' by means of suitable bolts. The driving drum 26 is rotatably supported in these brackets and through the belts shown drives the cutter spindles. As has been heretofore stated, the cutter-supporting member 3, as well as the table 11, is also mounted directly on the machine body. It will be seen that by this construction, all the main movable parts of the machine are mounted separately on the body whereby the vibratory effect of one on the other is reduced to a minimum, such feature being of particular importance in a machine of the type illustrated.

As a further means of improving the construction of the present machine, I provide a novel form of mounting for the former pin blocks, such mounting being shown in all the views of the drawing as a part of the present machine. As is usual in this type of machine I provide a former pin mounting on both sides of each cutting tool, such pins serving to operate on a right or left hand pattern respectively. Referring particular-

ly to Figs. 7 and 8 wherein I have illustrated the former pin construction in detail, 8 illustrates the tool spindle mounted in the vertically slideable tool head 7. Each side 5 of the head 7 is recessed as at 27 within which I preferably mount the former pin block 28, each block having a former pin as 29 secured therein by means of the clamping bolts 30. Each block is preferably recessed laterally as at 31, such recess being 10 adapted to receive therein means, such as a pin or bolt 32, whereby the block is prevented from vertical movement within the recess 27 but may be readily removed when 15 desired.

I secure the block in the recess 27 by a clamping means including a clamping screw threaded into the head 7, the arrangement of the clamping means being such that the 20 block is crowded or wedged into the recess in a manner to fully prevent any lateral movement thereof. This clamping means preferably comprises a curved clamping head 33 mounted on the bolt 34, such head being 25 adapted to engage the block adjacent one corner thereof and to force the block securely into the opposite corner of the recess. As shown in Fig. 7, I also preferably chamfer off the block as at 35 and the adjacent corner of the head as at 36 whereby to form a 30 recess to receive the clamping head 33 in a wedging position therein.

As a means for adjusting the block laterally relative to the tool spindle 8, I prefer 35 herein to provide a taper gib or wedge, as 37, the side of the block adjacent to the gib being likewise inclined or tapered to fit the gib. I also prefer to provide a positive means for adjusting the gib longitudinally 40 and as such a means for this purpose I herein illustrate a screw 38 threaded into the block and having a positive engagement with the gib, as by means of a flange 39 engaging a notch 40 in the gib. This construction provides a positive and accurate 45 means for adjusting the gib in both directions longitudinally. After the block is adjusted to the desired position, the clamping bolt 34 is tightened and the block thereby 50 forced tightly into the opposite corner of the recess and against the gib 37. As will be observed, this novel block mounting construction provides for a very fine and accurate adjustment of the block laterally in the 55 recess, prevents the block from any vertical movement, and provides a means whereby the block may be securely clamped against any lateral movement in the head 7.

From the above description taken in connection 60 with the drawing it is thought that the general operation of the improved machine and the advantages of the present improvements thereon will be readily understood. However while I have illustrated the invention as being carried out by certain

mechanism shown in the drawing, it should be clearly understood that the invention is not limited to such structure shown but may be varied within the scope of the appended claims. 70

What I claim is:

1. In a metal working machine of the class described, the combination of a base, a tool support, a work table adjacent thereto, a chip and oil basin beneath and extending outside of the work table, a reservoir in the base, and an oil-draining chip pan beneath and spaced from the basin, an opening to the outside being formed at such space to afford access to the oil-draining pan, the basin having a chip and oil channel leading to the oil-draining pan and the oil-draining pan being adapted to drain into the reservoir. 80

2. In a metal working machine of the class described, the combination of a base, a tool support, a work table adjacent thereto, a chip and oil basin beneath and entirely surrounding the work table, a reservoir in the base, and an oil-draining chip pan beneath 90 and spaced from the basin, an opening to the outside being formed at such space to afford access to the oil-draining pan, the basin having a chip and oil channel leading to the oil-draining pan and the oil-draining pan 95 being adapted to drain into the reservoir.

3. In a metal working machine of the class described, the combination of a base, a column supported thereon, a tool support, a work table adjacent thereto, a chip and oil basin integral with the column and beneath and entirely surrounding the work table, a reservoir in the base, and a removable oil-draining chip pan beneath and spaced from the basin, an opening to the outside being 100 formed at such space through which the oil-draining pan may be removed, the basin having a chip and oil channel leading to the oil-draining pan and the oil-draining pan 105 being adapted to drain into the reservoir. 110

4. In a metal working machine of the class described, the combination of a base, a supporting column rising from the base, a tool support, a work table adjacent thereto, a chip and oil basin beneath and extending outside of the work table and projecting over a portion of the base, a reservoir in the base and an oil-draining chip pan outside the column and beneath the basin, the basin having a chip and oil channel leading to the oil-draining pan and the oil-draining pan 115 being adapted to drain into the reservoir. 120

5. In a metal working machine of the class described, the combination of a base, a supporting column rising from the base, a tool support, a work table adjacent thereto, a chip and oil basin supported on the column beneath and extending outside of the work table and projecting over a portion of the base, a reservoir in the base, the reservoir 125 130

- having an oil-draining port through the base under the said basin outside the column, and an oil-draining chip pan adapted to be removably mounted in the port, the basin
6. In a profiling machine, the combination of a base, a column supported thereon, a work table supported by the base, a horizontal cutter-supporting rail mounted on the column, a cutter-supporting saddle slidably mounted on the rail, a chip and oil basin beneath and surrounding the work table and having a chip and oil-draining channel leading therefrom, and a baffle-plate at each side of the machine beneath the end portions of the rail, such plates projecting into the basin and serving to direct into the basin any oil dripping from the said end portions.
7. In a profiling machine, the combination of a base, a column supported thereon, a work table supported for rectilinear movement on the column, a chip and oil basin supported by the base beneath and extending outside of the work table, a cutter-supporting guide supported on the column within the basin, a cutter-supporting saddle slidably embracing the guide and movable thereon in a direction at right angles to the movement of the table, a vertical cutter spindle mounted in the saddle over the table, and means for driving the cutter spindle, the size and arrangement of the basin being such that it extends beneath the work table and saddle in all their operative positions.
8. In a profiling machine, the combination of a base, a column supported thereon, a work table supported on the column, a chip and oil basin integral with the column and beneath and entirely surrounding the work table, cutter-supporting guides supported respectively on the column at opposite sides of the table and within the outlines of the basin, the table in operation being movable between such supports, a cutter-supporting saddle slidably embracing the guide and movable transversely of the table, a vertical cutter spindle mounted in the saddle over the table, and means for driving the cutter spindle in all its positions along the guide.
9. In a profiling machine, the combination of a base, a column supported thereon, a work table supported on the column, a chip and oil basin integral with the column and beneath and entirely surrounding the work table, a cutter-supporting member mounted on the column within the outlines of the basin and comprising upper and lower guide rails, a cutter-supporting saddle slidably embracing the rails, a cutter spindle supported on the saddle, a drive pulley on the spindle, brackets mounted on the column, a driving drum mounted in the said brackets, and a belt passing around the drum and pulley for driving the cutter spindle.
10. In a profiling machine, the combination of a base, a work table supported by the base, a cutter-supporting member comprising upper and lower guide rails having a horizontal elongated opening therebetween, a cutter-supporting saddle slidably embracing the rails, a vertical cutter spindle supported on the saddle, a projection on the saddle extending over the top surface of the lower rail, a taper gib adjustably mounted between the upper surface of the lower rail and the said projection to adjust the saddle on the rail, the said gib extending entirely across the saddle, a screw engaging the gib and saddle to adjust the gib longitudinally, and means projecting through the elongated opening and operatively connected to the cutter spindle whereby the spindle is driven in all its positions along the rails.
11. In a profiling machine, the combination of a cutter head having a recess therein, a former pin block mounted in the recess, means to secure a former pin in the block, means for preventing vertical movement of the block in the head, and means engaging one corner of the block to hold the block securely seated in the opposite corner of the recess.
12. In a profiling machine, the combination of cutter head having a recess therein, a former pin block mounted in the recess and having one corner thereof chamfered off, means to secure a former pin in the block, means for preventing vertical movement of the block, and screw threaded means engaging the said chamfered off portion of the block to hold the block securely seated in the opposite corner of the recess.
13. In a profiling machine, the combination of a cutter head having a recess therein, a former pin block mounted in the recess and having one corner thereof chamfered off, the adjacent corner of the head also being chamfered off, means to secure a former pin in the block, means for preventing vertical movement of the block, an element engaging the two chamfered off surfaces to wedge the block in the recess, and screw threaded means for forcing and holding the element in such engagement.
14. In a profiling machine, the combination of a cutter head having a recess therein, a former pin block mounted in the recess, means to secure a former pin in the block, means for preventing vertical movement of the block, a taper adjusting gib between the block and the head, and means to hold the block against the gib in the recess.
15. In a profiling machine, the combination of a cutter head having a recess therein, a former pin block mounted in the recess, means to secure a former pin in the block,

- means for preventing vertical movement of the block, a taper adjusting gib between the block and the head, and means engaging one corner of the block to hold the block securely seated in the opposite corner of the recess and against the gib.
16. In a profiling machine, the combination of a cutter head having a recess therein, a former pin block mounted in the recess, means to secure a former pin in the block, means for preventing vertical movement of the block, a taper adjusting gib between the block, and the head, means to adjust the gib longitudinally, and means to hold the block against the gib in the recess.
17. In a profiling machine, the combination of a cutter head having a recess therein, a former pin block mounted in the recess, means to secure a former pin in the block, means for preventing vertical movement of the block, a taper adjusting gib between the block and the head, a screw engaging the block and gib for adjusting the gib longitudinally, and means to hold the block against the gib in the recess.
18. In a profiling machine, the combination of a cutter head having a recess therein, a former pin block mounted in the recess, means to secure a former pin in the block, means for preventing vertical movement of the block, a taper adjusting gib between the block and the head, a screw threaded into the block and having engagement with the gib whereby the gib may be adjusted longitudinally in both directions, and means to hold the block against the gib in the recess.
19. In a profiling machine, the combination of a cutter head having a recess therein, a former pin block mounted in the recess and having a lateral opening extending into the block along one side thereof, means to secure a former pin in the block, means passing through the said opening to prevent vertical movement of the block, and means engaging the exterior of the block for securing the block in the recess.
20. In a profiling machine, the combination of a cutter head having a recess therein, a former pin block mounted in the recess and having a lateral opening extending into the block and horizontally along one side thereof, means to secure a former pin in the block, a bolt passing through said opening to prevent vertical movement of the block, and means engaging one corner of the block to hold the block securely seated in the opposite corner of the recess.
21. In a profiling machine, the combination of a cutter head having a recess therein, a former pin block mounted in the recess and having a lateral elongated opening extending into the block and horizontally along the inner side thereof, means passing through said opening to prevent vertical movement of the block, a taper adjusting gib between the said inner side of the block and the head, and means to hold the block against the gib in the recess.

In testimony whereof, I hereto affix my signature.

J. J. THACHER.
